ARTICLE AND QUANTITY DESIGNATOR FOR MENUS AND THE LIKE

Filed Nov. 6, 1931

UNITED STATES PATENT OFFICE

LOUIN BERRY, OF FORT WORTH, TEXAS

ARTICLE AND QUANTITY DESIGNATOR FOR MENUS AND THE LIKE

Application filed November 6, 1931. Serial No. 573,346.

This invention relates to mechanical indicators and it has particular reference to a menu card, or the like, capable of use in restaurants, sandwich shops, soda fountains 5 or other places where food or drinks are dispensed and sold and where it is desirable to provide a list of the commodities, and its principal object resides in the provision of a mechanical means whereby a customer may 10 indicate the articles which he desires to purchase, upon a bill of fare or menu, by the manipulation of certain movable elements.

Another object of the invention resides in 15 the provision of a device whereby a customer in a food dispensary, or the like, may select, upon the menu of such dispensary, certain articles of food or drink, indicating each selection for reference of the attendants without the necessity of verbal orders, and which 20 will result in a saving of time by both the customer and the attendant.

Still another object of the invention is 25 manifest in the provision of a combination of elements calculated to afford a quick means for recording and future reference certain ones of numerous items arranged in superimposed relationship and printed or otherwise permanently recorded upon the device.

Broadly, the invention seeks to comprehend 30 the provision of a device of the character described wherein are arranged certain movable elements, bearing configurations by which certain items may be selected from a 35 list of several items, indicating upon each selection the quantity desired.

While the foregoing objects are paramount, other and lesser objects will become manifest as the description proceeds taken in 40 connection with the appended drawing wherein:

Figure 1 is an elevational view of the invention showing the arrangement of slots and the figured slidable indicators, certain ones 45 of which are arranged opposite the items on the list.

Figure 2 is a cross section of the invention taken on line 2—2 of Figure 1, showing the indicators.

Figure 3 illustrates the manner in which

the invention may be held in the hands when operating the same.

Figure 4 is an enlarged fragmentary perspective view of the top of the invention.

Figure 5 is an enlarged fragmentary cross 55 sectional view of the invention showing the indicators in the slots, one of which is held therein by the tensioning means, and

Figure 6 is a perspective view of the preferred form of sliding indicators, showing 60 the square neck portion to prevent rotation in the slots.

Among dispensaries of food and other refreshments, a form of service has been inaugurated during the last few years known as 65 "curb service". Attendants which are usually assigned to take care of those seeking such services are sometimes called upon to stand by and wait several minutes for customers to decide which of the items on the menu he desires, resulting in a loss of time which should have been spent attending other customers. The present invention therefore, is designed to permit the customer as much time as he desires to make his selection without consuming 70 too much of the attendant's time, and provides also a device which can be used as an advertising medium.

Accordingly, the invention consists of a 75 mounting 1, of sheet metal, or the like, preferably of greater length than width. A slot 2 is provided and arranged longitudinally of the mounting 1 adjacent one edge of the latter as illustrated in Figure 1. The slot 2 extends substantially the full length of the 80 mounting 1 and communicates at either end with lateral slots 3 which extend transversely of the slot 2 and terminate at the approximate center of the mounting 1 near the top and at the bottom of the latter.

As previously pointed out, the invention is 85 particularly adapted to use as a menu card and since it is desirable to change the listing thereon from time to time, an interchangeable card 4, of pasteboard, or the like, is secured to the mounting 1 by means of the crimped edge 5 of the mounting 1 arranged 90 opposite to the slot 2, previously referred to, and a multiplicity of tongues 6, which latter are cut from the mounting 1 along one 95 100

edge of the slot 2, as shown in Figures 1 and 4.

When the tongues 6 have been stamped, or otherwise cut, from the mounting 1 they are 5 pressed upward and turned back away from the slot 2 to provide a means for holding the edge of the card 4 opposite to the crimped edge 5 of the mounting 1, previously referred to. When these tongues 6 are turned back a 10 series of short slots 7 are provided which communicate with and extend laterally from the slot 2, as shown in Figure 1. The card 4 is further retained in position upon the mounting 1 by a clip 8 which is, preferably, 15 cut from the mounting 1 and turned upward and over the edge of the card 4.

Slidably arranged within the lateral slots 3, communicating with the slot 2 at either end of the latter, are indicators 9, each of 20 which bear numerals *a*, or other indicia, as shown in detail in Figure 6. The indicators 9 are preferably semi-spherical in shape and provided with a square shank portion *b* to prevent their rotation in the slots 2, 3 and 7, 25 so that the indicia *a* will remain in an upright position relative to the mounting 1.

In operation, when the invention is used as a menu, as illustrated in the drawing, 30 selections are made from the items printed or otherwise placed upon the card 4, indicators 9 may be selected according to the indicia *a* thereon and engaged by the thumb of the left hand, as illustrated in Figure 3, and withdrawn from the lateral slots 3 into the 35 longitudinal slot 2 whereupon the indicator 9 can be brought opposite one of the items on the card 4 and passed into the lateral slot 7 opposite the said item and, upon being 40 pressed inwardly toward the card 4 will engage the top of the tongues 6, previously referred to, holding the indicator 9 firmly in place until it has been dislodged by manual effort. Obviously, for example, if the party 45 of customers is composed of five members, an indicator 9 bearing the indicia *a*, which is the numeral "2", can be placed opposite the item "Baked ham", which will indicate that two of this item are desired, and another of the indicators 9 bearing the numeral "3" 50 can be placed opposite the item "Ham-burger", which will indicate that three of the latter item are desired by the party. In other words, the quantity of each item selected on the card 4 by the parties ordering may 55 be indicated by placing opposite thereto one of the numbered indicators 9 in the manner above referred to.

By particular reference to Figures 2 and 5, it will be seen that the square shank portion 60 *b* of the indicators 9 is of such length as to allow the latter to extend beyond the under surface of the mounting 1 a sufficient distance to enable the semi-spherical head of the indicator 9 to be forced upon the tongues 6, 65 as illustrated particularly in Figure 2, and

frictionally engage the latter to hold the indicator 9 in position in the slot 7 until it has been removed therefrom. Figure 5 illustrates one of the indicators 9 in normal position in one of the slots 3, while the other indicator 9 is shown in position in one of the slots 7 in frictional engagement with one of the tongues 6. The indicator 9 is held within the slots 1, 70 3, and 7 by means of a washer *c* bradded, or otherwise secured to the lower end of the shank *b*.
75

As apparent in Figure 1, sufficient space 80 may be provided at either end of the invention for advertising purposes thereby providing a novel advertising medium for commodities such as foods, drinks and confections.
85

As previously pointed out the card 4 may be inserted by sliding the bottom end of the latter into crimp 5 along the edge of the mounting 1 and beneath the tongues 6, which latter are arranged along the edge of the mounting 1 opposite to the crimp 5 and downward until the bottom edge of the card 4 is seated behind the clip 8.
90

Although the invention has been described with great particularity, it is understood that certain changes and modifications may be resorted to from time to time provided such changes and modifications are deemed within the scope and meaning of the appended claims.
95

What is claimed is:

1. In a mechanical menu, a mounting for a lettered and figured card, the former having a slot arranged parallel and adjacent to the said card, a series of lateral slots extending from the said first slot opposite each of the letters and figures on said card, the material cut from said lateral slots being turned back on the said mounting to hold the said card, figured indicators slidable in the said slots and means to hold the said indicators in the said lateral slots when arranged therein.
100

2. A mechanical indicating apparatus comprising a mounting of semi-rigid material having a longitudinal slot arranged along and adjacent to one of its edges, a series of laterally directed slots communicating with the said longitudinal slot, a series of tongues projecting from each of the said laterally directed slots capable of engaging the edge of a removable card having indicia, a multiplicity of indicators movably disposed within the said slots capable of being moved opposite the said indicia on the said card and being frictionally secured therein until manually dislodged.
105

3. A mechanical indicating device having a mounting of semi-rigid material, a longitudinal slot extending along and adjacent to one edge of the said mounting, a multiplicity of slots extending laterally from the said longitudinal slot, tongues projecting from 110

each of the said lateral slots capable of overlapping a removable card having configurations thereon and a multiplicity of movable indicators arranged in the said slots and capable of being arranged opposite the said configurations on the said card and secured therein until manually dislodged.

4. A new article of manufacture, a mechanical menu comprising a mounting of 10 semi-rigid material, a slot extending longitudinally of the said mounting along and adjacent to one edge thereof, a series of slots projecting laterally from the said first named slot each having a tongue of material cut 15 therefrom in the mounting and turned back upon the said mounting, a card having indicia thereon capable of being disposed beneath the said tongues to hold the said card in position upon the said mounting and the 20 indicia upon the said card opposite each of the said last named slots and movable indicators disposed within the said slots capable of being arranged opposite the said indicia and secured against displacement until 25 manually removed.

5. A new article of manufacture, a mechanical indicating device having a semi-rigid mounting, a slot arranged along one edge longitudinally of the said mounting, 30 lateral slots extending from the said first named slot having a fragment of material cut from the mounting in the production of the said lateral slots turned back upon the said mounting, a card having indicia thereon 35 interchangeably secured to the said mounting by the said fragments of material and movable indicators arranged in the said slots capable of being placed opposite the said indicia in the said slots and frictionally secured against displacement by reason of the 40 said fragments of material.

6. A mechanical indicating apparatus having a semi-rigid mounting, a slot arranged longitudinally of the said mounting and adjacent to one edge thereof, a multiplicity of 45 lateral slots communicating with the first named slot, tongues cut from the mounting in each of the said last named slots turned back upon the mounting, an interchangeable card 50 having indicia thereon arranged upon the said mounting and secured in position by the said tongues and movable figured indicators disposed within the said slots and capable of arrangement opposite the said indicia on the said card and frictionally secured therein until manually dislodged.

In testimony whereof I affix my signature.
LOUIN BERRY.
